Attoys.

UNITED STATES PATENT OFFICE

WILLIAM W. CARGILL, OF MADISON, WISCONSIN, ASSIGNOR TO FRENCH BATTERY COMPANY, OF MADISON, WISCONSIN, A CORPORATION OF WISCONSIN

FLASH LIGHT

Application filed October 1, 1930. Serial No. 485,765.

This invention relates particularly to flashlights of the type which permit the lamp to be turned at an angle to the axis of the casing, when desired.

5 The primary object is to provide a thoroughly practicable flashlight of the character indicated which is of staunch and durable character, and which serves effectively as an ordinary flashlight, but which, by a simple 10 manipulation, may be changed to enable the axis of the lamp to be set at an angle to the axis of the main casing.

The invention is illustrated in a preferred embodiment in the accompanying drawings, 15 in which—

Fig. 1 is a broken vertical sectional view of a flashlight embodying the invention; Fig. 2, a transverse section taken as indicated at line 2 of Fig. 1, and Fig. 3, a detail elevational view of the support which carries the 20 tiltably mounted head employed.

In the illustration of the invention given in the drawing, A designates a main casing-section equipped with an extension-section 25 A'; B, a lamp-carrying head mounted on a bracket B' which is pivotally supported on a short standard B² carried by a support B³ detachably connected with the upper end of the main casing-section A; and C, a battery comprising a dry cell, or dry cells, 30 housed within the main casing-section.

The casing-section A is shown equipped at its lower end with a removable cap 1, within which is located a spring 2 which forms electrical connection between the zinc bottom of the lowermost cell and the casing.

The upper end of the casing-section A is provided, as indicated at 3, with a corrugated thread-portion.

40 The casing-extension A' comprises a tubular member having its upper end abutting against the lamp-carrying member B, and having its lower end provided with a corrugated thread-portion 4 which engages the 45 thread 3. The casing-extension A' may be screwed downwardly until the thread-portion 4 becomes disengaged from the thread-portion 3 of the main section, and the extension A' may then be slid downwardly into 50 a telescoped position to enable the head B to

be turned at an angle to the axis of the flashlight casing.

The lamp-supporting head B is shown as consisting of a cupped sheet-metal member having its bottom provided with a central 55 opening equipped with an insulation ring 5 in which is supported a metal lamp socket 6.

The outer open end of the cupped member B preferably is provided with a corrugated thread-portion 7, upon which is adjustably mounted a focusing sleeve 8 which carries a reflector 9 and a glass-disk, or lens 10. The bottom of the reflector 9 is provided with a perforation 9^a through which the lamp bulb 11 mounted in the socket 6 protrudes into the 65 reflector. Focusing, where this feature is desired, may be accomplished by the means disclosed.

The lamp socket 6 is provided with a depending extension 6^a in the lower end of 70 which is fitted an insulation disk 12 through which extends a contact 13 with which is connected a conductor 14.

The bracket B' is shown as a furcated member comprising a head portion 15 which conforms to the part-spherical bottom of the member B and is secured thereto, as by means of rivets 16.

The bracket B² comprises a sheet-metal strip bent into suitable form and secured to 80 the member B³ as by means of rivets 17. Furcations of the member B' embrace the standard portion of the member B², and the parts are firmly connected by a rivet 18 which serves as a pivot. The connection preferably 85 is sufficiently tight to develop a suitable amount of friction so that the head B will remain at any desired angle at which it may be set.

The support B³ is shown as comprising a 90 sheet-metal disk 19 having a flange 19^a which is corrugated to form a thread which engages the thread-portion 3 of the main casing-section; and an insulation disk 20 secured to the disk 19, the disk 19 being provided with a central opening which is covered by the insulation disk 20. Through the insulation disk 20 extends a central contact 21 which is electrically connected with the 95 wire 14.

The battery C is shown as comprising two dry cells 22 having central contacts or electrodes 22^a, the central electrode of the upper cell making contact with the central contact 21, and thus being electrically connected, through the medium of the wire 14 and the contact 13, with the central contact 23 of the lamp.

The metal socket 6 makes contact with the outer terminal of the lamp. This socket is electrically connected at 24 with an insulated wire 25 which extends through an insulation ferrule 26 with which the disk 19 is equipped.

The lower or inner end of the conductor 25 affords a contact 25^a which makes contact with the upper end of a conductor 27 (suitably insulated) which is connected with the casing, the conductor 27 leading to the switch 28 which is equipped with a sliding switch member 29 electrically connected to the casing and adapted to close the circuit at the point 30.

Preferably, the member B³ is equipped with a pivotally mounted foot, or support, 31, which normally is housed within the casing-section A'.

The member 31 is shown as consisting of a wire bent into suitable shape to provide feet 31^a and pivot-portions 31^b, the pivot-portions extending through pivot-members 32 and riveted thereat, these connections preferably being sufficiently tight to hold the member 31 in any desired position of adjustment.

After the sleeve A' has been completely telescoped on the main casing-section A, the support 31 may be swung in one direction to provide a protruding foot or support, and the lamp-head B may be swung in the opposite direction. Thus, for example, the pivot support 31 may support the flashlight on its side, while the lamp is directed laterally with relation to the flashlight body. That is, the flashlight body may rest on its side with one end supported on the member 31, while the lamp is directed upwardly.

When the flashlight is in use as an ordinary flashlight, the casing-extension A' is in the position shown in Fig. 1, in which it firmly supports the lamp-head B and houses the internal connections. In this condition, the flashlight has much the appearance of an ordinary flashlight, perhaps of special construction. On the other hand, the sleeve A' may be caused to telescope fully with the upper portion of the main-casing section A of the flashlight casing, thus permitting the lamp to be turned at an angle to the body of the flashlight and supported as explained above.

The pivotal support 18 of the lamp-head B is eccentrically located, as shown in Fig. 1. That is, the pivot is shown located near one side of the casing, and this is the preferred arrangement.

While the invention is shown applied to a flashlight in which one terminal of the lamp

is grounded on the casing, it is obvious that any other desired arrangement may be used; and, if desired, a non-metallic casing may be employed, in which event suitable circuit connections may be provided in a manner well understood in the art.

The foregoing detailed description has been given for clearness of understanding only and no unnecessary limitation should be understood therefrom, but the appended claims should be construed as broadly as permissible, in view of the prior art.

What I regard as new and desire to secure by Letters Patent, is:

1. A flashlight comprising a main casing-section equipped with a support; a lamp-head carried by said support and adapted to be turned at an angle to the axis of the main casing-section; and a tubular casing-extension telescopically related to the main casing-section and adapted to bridge the space between the lamp-head and main casing-section.

2. A flashlight as specified in claim 1, in which the casing-extension is rotatably and slidably mounted on the main casing-section.

3. A flashlight as specified in claim 1, in which the support mentioned and the lamp-head are equipped with pivotally connected bracket-members.

4. A flashlight as specified in claim 1, in which the support mentioned and the lamp-head are equipped with pivotally connected bracket-members which are eccentrically disposed.

5. A flashlight comprising: a main casing-section; a tubular casing-extension telescopically related to the main casing-section; a support engaging the inner surface of the end-portion of the main casing-section and equipped with a central contact; a cupped lamp-head; mounting-connections tiltably supporting said head and carried by said support and normally disposed within said casing-extension; a lamp-socket carried by said lamp-head and equipped with a central contact electrically connected with said first-mentioned central contact; and an electric conductor connected with said socket and extending downwardly into the main casing-section.

6. A flashlight as specified in claim 5, in which the electric conductor leading from said socket is equipped below said support with a contact, and in which the main casing-section is equipped with a switch and with a conductor leading therefrom and provided with a contact co-acting with the contact just previously mentioned.

7. A flashlight comprising a main casing-section equipped with a support; a lamp-head; mounting connections carried by said support and tiltably supporting said head; a casing-extension telescopically related to the main casing-section and bridging the

space between said head and the main casing-section; and a normally housed movably mounted support adapted to be projected laterally with relation to the main casing-section when the casing-extension is in telescoped position.

8. A flashlight as specified in claim 7, in which the movably mounted support mentioned is pivotally secured to the support carried by the main casing-section.

9. A flashlight as specified in claim 7, in which the mounting-connections for the lamp-head comprise a bracket-member secured to the head, a bracket-member secured to the support carried by the main casing-section, and a pivot connecting said bracket-members.

10. A flashlight as specified in claim 7, in which the mounting-connections for the lamp-head comprise a bracket-member secured to the head, a bracket-member secured to the support carried by the main casing-section, and a pivot connecting said bracket-members, and in which the pivot is eccentrically positioned near one side of the casing and the support carried by the main casing-section is equipped with a movably mounted supporting member adapted to be projected (when the casing-extension is in telescoped position) at the opposite side of the casing.
